United States Patent Office

Des. 230,24

Patented Feb. 5, 197-

230,241

PRODUCE GRATER

Frederick W. Riddington, Ontario, Calif., assignor to Sunkist Growers, Inc., Sherman Oaks, Calif.

Filed Apr. 5, 1972, Ser. No. 241,487

Term of patent 14 years

Int. Cl. D7—04

U.S. Cl. D7—47

FIG. 1.

FIG. 2.

FIG. 3.

FIG. 4.

FIG. 5.

FIG. 1 is a perspective view of the produce grater showing my new design;

FIG. 2 is a bottom plan view thereof;

FIG. 3 is a rear elevational view thereof;

FIG. 4 is a left end elevational view of FIG. 3; and
FIG. 5 is a left end elevational view of FIG. 1.

I claim:

The ornamental design for a produce grater, as shown.
